UNITED STATES PATENT OFFICE.

HARRY FERDINAND LEISSNER, OF SÖDERTÄLJE, SWEDEN.

INTERNAL-COMBUSTION ENGINE

1,401,089.

Specification of Letters Patent. Patented Dec. 20, 1921.

Application filed November 15, 1920. Serial No. 424,172.

To all whom it may concern:

Be it known that I, HARRY FERDINAND LEISSNER, a citizen of the Kingdom of Sweden, residing at Södertälje, Sweden, have invented new and useful Improvements in Internal-Combustion Engines, of which the following is a specification.

In the patent No. 1,136,818 there is described an internal combustion engine having a primary explosion chamber divided into two compartments arranged concentrically to each other, the inner one of said compartments communicating directly with the cylinder chamber, while the outer compartment communicates with the said inner chamber only.

In machines constructed in accordance with said patent I have found that fluid oil may collect in the said outer compartment when the engine is running light, and will cause racing of the engine when the fuel supply is cut off.

To overcome said inconvenience there is provided according to this invention a direct connection between the said outer compartment and the cylinder chamber to prevent unburned fuel oil from collecting in said outer compartment.

In the accompanying drawing I have shown one embodiment of my invention. Figure 1 is a diagrammatical longitudinal section of an internal combustion engine constructed according to said invention. Fig. 2 is an enlarged sectional view of the uppermost portion of the same engine.

The numeral 1 represents the cylinder chamber of the engine communicating constantly with the inner compartment 4 of a primary explosion chamber comprising the two compartments 4 and 5 arranged concentrically to each other, and separated from each other by a sleeve 3, communication between the said compartments being provided by a space at the top of the sleeve as well as by apertures formed in the walls of said sleeve.

According to this invention not only the inner compartment 4 but also the outer compartment 5 of the primary explosion chamber communicates directly with the cylinder chamber 1, the connection between the compartment 5 and the cylinder chamber being formed by the two holes or channels 6 and 7. It is evident that the position and number of such holes or channels may be chosen at will.

The general outlines of the operation of that kind of engines to which the invention is applied are described in the Patent 1,136,818. Due to the provision of such channels 6 and 7 any fuel oil tending to collect in the compartment 5 will flow through the channels into the cylinder chamber thereby eliminating the tendency for racing of the engine above referred to.

It is obvious that the invention may be applied not only to vertical engines but also to horizontal engines; the only requirement to be satisfied in both cases being that the channels 6 and 7 are arranged vertically or inclined so as to permit fuel oil to flow from the compartment 5 into the cylinder chamber.

Having now described my invention, what I claim is:

In an internal combustion engine, the combination of a cylinder chamber, a primary explosion chamber, a sleeve in said primary explosion chamber secured to the bottom of said chamber and ending at a distance from the top thereof, the two compartments of said primary explosion chamber formed by the said sleeve communicating with each other through openings in the sleeve and further communicating separately with the said cylinder chamber.

In testimony whereof I have signed my name.

HARRY FERDINAND LEISSNER:
